VENETIAN BLIND

Paul Lippert, Chicago, Ill.

Application July 31, 1944, Serial No. 547,421

9 Claims. (Cl. 160—173)

1

This invention relates to improvements in Venetian blinds and it consists of the matters hereinafter described and more particularly pointed out in the appended claims.

Venetian blinds, as at present constructed, generally include a tilting rail, foot rail and slats which are supported by ladder tapes that are physically attached to the rails as by tacks or the like. Blinds of this kind are quite difficult to satisfactorily clean when soiled, because they must be first disassembled by removing the physical attachment and then replacing the same after assembly, with frequent misadjustment and misalignment of the parts so that the blind not only hangs improperly, but is difficult to operate.

To replace certain worn parts or to clean Venetian blinds as now made, requires skill and the use of tools, neither of which is generally available in the average home wherein such blinds are used. Therefore, large establishments have been built up to remove the blinds as a whole from the home to said establishment where they are cleaned and thereafter returned to the home and rehung or replaced. This entails considerable expense and inconvenience.

One of the objects of the present invention is to provide a novel arrangement of parts in a Venetian blind, by which the blind may be quickly and easily disassembled so that worn or damaged parts may be replaced, or the blind may be readily cleaned on the premises and replaced properly without the aid of tools and without the necessity of skill in this kind of work.

Another object of the invention is to provide an improved ladder tape for such blinds which requires no physical attachment to the tilting and foot rails of the blind and which will not become displaced after the operating cords have been arranged in position in the blind.

Also, it is an object of the invention to provide a simple and efficient structure whereby the operating cord may be readily detached from and reattached to the foot rail of the blind without the use of tools.

The above mentioned objects of the invention, as well as others, together with the advantages thereof, will more fully appear as the specification proceeds.

In the drawing:

Fig. 1 is a view in elevation of a Venetian blind embodying the preferred form of the invention.

Fig. 2 is a vertical sectional view through a part of the blind as taken on the line 2—2 of Fig. 1 and on a scale enlarged thereover.

Fig. 3 is a horizontal detail sectional view

2

through a part of the blind, on substantially the scale of Fig. 2, as taken on the line 3—3 of Fig. 1.

Fig. 4 is a detail vertical sectional view through a part of the blind shown in Fig. 2 as taken on the line 4—4 thereof on a further enlarged scale.

Fig. 5 is a perspective view of a certain endless ladder tape embodied in the improved blind construction.

Fig. 6 is a perspective view of a certain toggle head on one end of the operating cord.

Fig. 7 is a view similar to Fig. 6 showing a modified construction of toggle head later to be mentioned in more detail.

Referring now in detail to that embodiment of the invention illustrated in Figs. 1 to 6 inclusive of the drawing, 10 indicates the head rail of a Venetian blind, 11 and 12 indicate the tilting and foot rails respectively of the blind, and 13—13 indicate the ladder tapes thereof, which operatively support the slats 14 in the space between the tilting and the foot rails.

The tilting rail has end trunnions 15 and 16 respectively, which removably bear in brackets 17 and 18 depending from the head rail. Associated with the bracket 17 is a suitable means 19 operatively connected to the trunnion 15 and whereby a tilting movement may be imparted to the rail 11 in one direction or the other when said means is actuated by a cord 20.

Each ladder tape 13, which best appears in Fig. 5, is made in the form of an endless loop, and comprises front and rear sides 21—22 and top and bottom end loops 23 and 24 respectively. The sides of each tape are operatively connected together by means of slat supporting rung-like cross pieces 25. Said cross pieces are arranged in staggered relation so that the alternate ones are disposed along one edge of both sides 21—22, and the intermediate ones are disposed along the other edge of said sides and in planes between those of the alternate pieces. Thus a passageway is afforded in the medial line of each tape for the operating cord 26 of the blind, later to be mentioned in more detail, and this passageway is in alignment with eyeleted openings 23a and 24a respectively in the end loops of the tape.

One portion of the operating cord 26 hangs from the bracket 18 as a loop within easy reach for the operator and said bracket includes means in which any part of the cord loop may be caught to hold the blind to the desired effective length. That part of the cord beyond the bracket forms two portions 27—27 one for each tape 13 and these two portions are disposed in guide grooves (not shown) in the head rail 10 to pass down-

wardly therefrom through openings in line with the associated tapes.

The bottom end extremity of each cord portion 27 is fixed in one end of a metallic sleeve 28, which sleeve carries a suitable piece or member which may be swung from a position parallel with the sleeve, wherein it forms a longitudinal continuation thereof, to a position standing crosswise of the other end of said sleeve. In the form shown in Fig. 6, said other end of the sleeve is longitudinally slit as at 29 to receive a flat piece or bar 30 which is pivoted at a point between its ends to said sleeve as at 31. In Fig. 7 the sleeve 28 requires no slit 29 because the piece, which is indicated at 30a, is semitubular so as to fit the outside of said sleeve and to which it is pivoted as at 31a.

To assemble the blind above described, the endless tapes 13-13 are each slipped onto the associated end of the tilting rail 11, when the latter has been removed from its hanger brackets 17 and 18, so that the end loops 23 of each tape passes over the top surface of the tilting rail. The end loops of both tapes are then so positioned on the tilting rail that the opening 23a of each loop registers with an opening 11a in the tilting rail and one of which openings appears in Fig. 2. It is pointed out that the loops 23 of the ladder tapes are in no manner physically attached to the tilting rail as by means of brads or tacks but have at this time only a hanging support therefrom.

The parts as shown in either Fig. 6 or 7, and which are fixed to the cord portions 27-27, are manipulated to close them. That is the members 30 or 30a are moved into the full line position shown in Figs. 6 and 7 and wherein they form longitudinal extensions for the associated sleeve. With the members in their so-called closed position, each one is inserted through an opening 23a in the loop 23 of its associated tape 13 and through the associated opening 11a in the tilting rail in line with said opening 23a. Thereafter said end portions 27 of the operating cord are pulled through said openings the desired distance or length, which is one substantially equal to the length of the respective tapes. Said rail is now replaced so that its trunnions 15 and 16 operatively bear in the brackets 17 and 18.

The foot rail 12 is now placed in the lower end loop 24a of both ladder tapes so that certain openings 12a-12a (only one of which appears in Fig. 2) coincide or align with the openings 24a in said loop ends of the ladder tapes. Thus, the tapes now support the foot rail, which in no manner is physically attached to said rail as by brads or tacks.

With the parts arranged as thus far described they are now disposed in a convenient and advantageous position for the insertion of the slats 14 into operative engagement with their respective supporting rungs or cross pieces 25-25 of the tapes 13-13 so that certain transverse openings 14a-14a (one of which appears in Fig. 3) are disposed in the plane of the cord passage-way as provided by the rungs or cross pieces 25-25.

With the slats 14-14 and foot rail thus supported from the tapes 13-13, the members on the cord portions are inserted through the openings 14a-14a in the successive slats 14, beginning with the topmost one, through to the bottommost one, and then through the openings 12a in the foot rail 12 and through the openings 24a in the loop ends 24 of the tapes to a point below 75

the same. Each member 30 (or 30a) may now be turned to its open position and wherein it extends across said opening so as to prevent the upward withdrawal from said tapes and foot rail. 5 It is obvious that the cord portions 27 in connection with the sleeves 28 prevent endwise shifting or turning of the tilting rail and the foot rail with respect to the tapes and which are in no manner physically attached to either rail as by means of tacks or brads.

The blind as a whole is now assembled and ready for operation. From the above it is obvious that assembly has been accomplished without the aid of tools of any kind and without the necessity of making any direct physical attachment of the tapes to either the tilting or to the foot rail, as by means of special clips or as by means of tacking the loops 23-24 of the tapes to said rails.

20 By pulling upon the loop of the cord 26, the cord portions 27-27 are drawn upwardly and with the members 30 (or 30a) engaged with the foot rail and tape loops 24 as before explained, said foot rail is drawn upwardly to pick up the lowermost slats in the usual manner.

25 It is obvious that the ladder tapes are in no manner physically attached as by tacks, brads or special clips to any part of the entire blind structure, but are held against endwise shifting and circumferential slipping or creeping about the tilting and foot rails by means of only the operating cord.

30 By manipulating the cord loop 20 the slats may be tilted to the desired inclination, as in any conventional blind arrangement.

35 Should the blind structure become soiled or damaged, it may be readily taken apart. To do this each blind is first lowered to its full length. The members 30 (or 30a) are then swung into 40 position so that when a pull is imparted to the cord 26, they will pass up through the openings in the tape portions 24 and in the foot rail, slats, tilting rail and other tape portions 23. The foot rail and the slats may now be removed from the 45 tapes, the tilting rail removed from its brackets 17 and 18 and the tapes then slipped endwise off said tilting rail.

50 It is to be noted that the Venetian blind described is equipped with endless ladder tapes, which are not physically attached to either the tilting rail or to the foot rail.

55 With the construction described, it is obvious that the blind may be readily taken apart for cleaning or repair or replacement of parts and this without the aid of tools of any kind and by a person not necessarily skilled in the Venetian blind art.

While in describing the invention I have referred in detail to the form, arrangement and construction of the parts involved, the same is to be considered only in the illustrative sense so that I do not wish to be limited thereto except as may be specifically set forth in the appended claims.

I claim as my invention:

1. In combination with the raising and lowering cord of a Venetian blind that includes a foot rail having an opening therein, means for detachably connecting one end of said cord to said foot rail, and including a member attached to the cord and swingable from a position substantially in line with the cord to facilitate passage through said opening in said foot rail to a position crosswise of the cord to prevent its withdrawal through said opening.

2. In combination with the raising and lowering cord of a Venetian blind that includes a foot rail having an opening therein, means for detachably connecting one end of said cord to said foot rail and embodying therein a sleeve attached to and forming a longitudinal continuation of said end of said cord, and a member pivotally connected to said sleeve and swingable from a position parallel with said sleeve for passage therewith through said opening in said foot rail to a position extending across and preventing its withdrawal through said opening.

3. In combination with the raising and lowering cord of a Venetian blind that includes a foot rail having an opening therein, means for detachably connecting one end of said cord to said foot rail and embodying therein a sleeve attached to and forming a longitudinal continuation of said end of said cord, and a member pivotally connected to said sleeve and swingable from a position embracing an outer portion of said sleeve for passage therewith through said opening in said foot rail to a position extending across and preventing its withdrawal through said opening.

4. A Venetian blind embodying therein tilting and foot rails each having openings therein, slats and endless loop-like ladder tapes, each tape including spaced sides and connecting end loops each having an opening therethrough, one end loop of each tape passing about the top of but physically unattached to the tilting rail and by which said tapes are supported, the other end loop of each tape passing about the bottom of but physically unattached to the foot rail for supporting the same, means extending between the spaced sides of each tape for the support of said slats, and a raising and lowering cord having portions one for each tape, each cord portion passing through said slats and through certain of said openings in said rails and through said openings in said end loops of the associated tape and forming the sole means for preventing displacement of said tapes relative to said rails.

5. A Venetian blind embodying therein tilting and foot rails each having openings therein, slats and endless loop-like ladder tapes, each tape including spaced sides and integral end loops each having an opening therethrough, one integral end loop of each tape passing about the top of but physically unattached to the tilting rail and by which said tapes are supported, the other integral end loop of each tape passing about the bottom of but physically unattached to the foot rail for supporting the same, means extending between the spaced sides of each tape for the support of said slats, and a raising and lowering cord having portions, one for each tape, each cord portion passing through said slats and through certain of said openings in said rails and through said openings in said end loops of the associated tape and forming the sole means for preventing displacement of said tapes relative to said rails.

6. A Venetian blind embodying therein tilting and foot rails each having openings therein, slats and ladder tapes, each tape including spaced

sides and end loops, one end loop of each tape passing about the top of but physically unattached to the tilting rail and by which said tapes are supported, the other end loop of each tape passing about the bottom of but physically unattached to the foot rail for supporting the same, means extending between opposite sides of each tape for the support of said slats, and a raising and lowering cord having portions, one for each tape, each cord portion passing through said slats and through certain of said openings in said rails and end loops of the associated tape and forming the sole means for preventing displacement of said tapes relative to said rails, and means carried by the bottom end of each cord portion adapted to pass through an opening in the foot rail and end loop of the tape associated therewith and turnable to a position crossing said opening to prevent its withdrawal therethrough.

7. A ladder tape for a Venetian blind comprising an endless loop-like tape member having spaced side portions and connecting end loop portions, means connecting the spaced side portions of said tape member and forming slat supporting rungs therefor, the end loop portions each having an opening therein for the passage therethrough of a blind operating cord portion.

8. A Venetian blind embodying therein a tilting rail and a foot rail, equipped with endless loop-like ladder tapes each including spaced sides and connecting end loops and which loops pass about said tilting rail and said foot rail but are not physically attached to either of said rails.

9. A Venetian blind embodying therein a tilting rail and a foot rail and slats arranged therebetween, said rails and slats having parts with sets of aligned openings therein, endless loop-like ladder tapes each having spaced sides and top and bottom loops connecting the associated ends of said sides and which loops are trained about but are physically unattached to said parts of said rails, the top and bottom loops of each tape each having openings therein that register with each set of openings in said rails and slats respectively, and a raising and lowering cord having portions each passing through a set of openings in said rails and slats as well as through the registering openings in the top and bottom end loops of said tapes and retaining said tapes against either a longitudinal or a lateral shifting relative to said rails.
